WARP STOP MOTION FOR LOOMS

John J. Kearby, Paterson, N. J.

Application October 20, 1936, Serial No. 106,598

3 Claims. (Cl. 139—355)

This invention relates to electrical warp stop motion mechanisms for looms and particularly mechanisms of this class in which the stopping action is brought into effect when a heddle in the heddle-supporting frames of the loom is allowed to fall by the breakage or undue slackening of the corresponding thread. One object is to provide an equipment of this class which is simple in construction and may be readily applied to any loom. To this end, each such frame is equipped with electro-conductive terminals insulated from each other and adapted to be bridged by a fallen heddle and with a contact electrically connected with one terminal, and on the supporting structure there is an abutment forming another contact electrically connected with the other terminal and adapted to be engaged by the contacts on the frames when the latter descend, the circuit formed when any frame descends and its heddle bridges the terminals including an electro-magnet which causes to go into action the means for effecting the stopping of the loom. In the preferred form the abutment is elastic and traverses the frames for a purpose to appear. The invention also contemplates a novel combination of parts useful in an electric stop motion system of the class in which the stopping is effected when a heddle frame descends with a heddle in fallen position therein, the same comprising, with a vertically reciprocating carrying structure including a substantially horizontal electro-conductive member (as a heddle bar), a substantially horizontal electro-conductive strip having a longitudinal heddle seat, which member and strip penetrate the heddles and are adapted to be bridged by a fallen heddle, and said structure insulating the member and strip from each other and also including clamping means for the strip exerting compression vertically thereon.

In the drawings,

Fig. 1 shows my mechanism as seen in a transverse section of the loom;

Fig. 2 is a fragmentary view on a larger scale showing a heddle frame and its equipment according to this invention the same as such appear in Fig. 1;

Figs. 3 and 4 are sections on lines 3—3 and 4—4, respectively, Fig. 2; and

Fig. 5 is a plan of a certain abutment and its bracket.

Each frame for supporting the heddles, or heddle-frame, is of the usual type comprising upper and lower horizontal wood rails 1, metal side bars 2 and metal heddle-bars 3 which are

held in the side bars by springs 4 and on which are adapted to be strung the heddles 5 so as to be capable of some vertical movement. The slot 5a of each heddle which receives the lower heddle-bar is appreciably elongated upwardly for a purpose to appear.

Driven into the lower rail 1 is a plurality of upstanding threaded and slotted posts 6 having nuts 7 thereon. These may be regarded as parts of the frame and they constitute means which, as will appear, serve to clamp in position a bar generally designated 8 and which in the present example penetrates the slots 6a of the posts, being above the lower heddle-bar which also penetrates said slots. This bar comprises two metal strips 8a and 8b, strip 8a being folded longitudinally of itself and forming a support for strip 8b with insulation 8c between them and the upper edge of strip 8b projecting above strip 8a. Strip 8b, whose top edge affords a seat on which a heddle (at the upper end of its slot 5a) may rest when it falls, forms one terminal of an electric circuit and, according as the post is made to contact strip 8a or the lower heddle bar, so one or the other of these latter forms the other terminal; in the present instance, since only the heddle bar so contacts with the post it forms such other terminal. The terminal 8b is insulated from the top nut 7 by a suitable washer 7a. So long as the heddles are supported by the corresponding warp threads they may only contact (at the sides of their slots 5a) with bar 8 as a terminal; otherwise the heddles may (at the upper ends of said slots) also contact the terminal 8b, thus closing said break and hence the circuit at this point. The frame as defined above and parts 1, 7a and 8a and the lower heddle bar form what I term a heddle carrying structure including a substantially horizontal electro-conductive member (said heddle bar) and in which an electro-conductive strip (as 8b), insulated from said member, is clamped by means (as the nuts) exerting compression vertically thereon. Terminal 8b protrudes from terminal 8a at one end and to it is there connected a conductor 9 which may penetrate the lower rail 1 and have a strip-like conductive contact 10 extending lengthwise of such rail.

Supporting structure is formed by the loom frame 11 including a cross-bar 12 to which are connected the usual springs 13 in turn connected to hooks 14 on the lower rails of the heddle-frames and acting normally to pull the latter down but yielding when the heddle-frames are raised by any suitable harness motion (not

shown) acting through cords 15. The left-hand side-bar 2 of each heddle frame is as shown connected to the near hook 14 by a wire 16.

To the loom frame 11 so as to be vertically adjustable is affixed a forked bracket 17 having its arms projecting inwardly and equipped with hooks 18 having nuts 19 thereon and which, as at 20, are insulated from the frame. Connecting these hooks so as to be below and so be engaged by the contact strips 10 of the several heddle-frames is a helical spring 21. A conductor 22 leads from one such hook to ground on the frame and it may contain a source of energy 23 and an electro-magnet 24. How the latter, when energized, causes stopping of the loom is not material; for instance, its armature, not shown, may act for that purpose substantially the same as in the patent to Pick, No. 683,491.

Operation.—Since stopping should not be effected when any heddle-frame is up and so the heddles bridge strip 8b and lower heddle bar due to the downward pressure of the warp the circuit is never adapted completely to be closed except when some heddle-frame is down, its terminal or contact strip 10 engaging spring 21, and then only if a warp thread corresponding to such heddle-frame has broken or is too slack so that the corresponding heddle is allowed to fall and contact both strip 8b and the lower heddle bar. In other words, each time a heddle-frame structure descends sufficiently to engage its contact strip with spring 21 the circuit is closed at that point but remains open at bar 8 unless a thread breaks or is too slack and so ceases to hold the corresponding heddle out of bridging relation to said strip and lower heddle bar.

When any heddle-frame is down the circuit is closed through conductors 22 and 9 and (if a heddle is also down) through the posts 6 and the lower heddle-bar 3 (with which such posts contact), the left side-bar of the heddle-frame, conductor 16, hook 14 and spring 13 back to ground. Of course the strip 8a may be electro-conductively connected with the abutment otherwise than as shown.

All parts by which strip 8a on the one hand and spring 21 on the other are grounded on the metal frame of the loom are of course conductive.

According to my invention element 21 forms a common circuit-closing medium for all the heddle-frames. It is yielding and preferably elastic to absorb the shock of the descending heddle-frames and so as to permit their vertical 55 adjustment relatively to each other as the weav-

ing needs require and still obtain their circuit-closing cooperation with said element. The threaded posts 6 and their nuts 7 permit adjustments of the circuit-closing bar vertically relatively to the heddle-bar.

Having thus fully described my invention what I claim is:

1. The combination, with a frame including horizontal rails, side bars connecting the rails and upper and lower heddle-bars connecting the side-bars, of another bar substantially parallel with and above the lower heddle-bar and including electro-conductive strips insulated from each other and one of which projects above the other, said frame also including means to support the second-named bar including threaded posts up-standing from the lower rail and nuts screwed on each post above and below such bar.

2. In an electric warp stop motion mechanism, the combination, with a vertically reciprocatory heddle carrying structure for electro-conductive heddles, said structure including an elongated substantially horizontal electro-conductive member and vertical threaded posts, of a substantially horizontal electro-conductive strip having a longitudinal heddle seat on which any fallen heddle may rest, said member and strip being adapted to penetrate heddles in said structure normally held elevated by the warp out of contact with said seat and to be bridged by a fallen heddle, and said structure insulating said member and strip from each other and also including nuts screwed on the posts and between which said strip is held clamped.

3. An electric warp stop motion mechanism including up-and-down-reciprocating frames for supporting heddles vertically movable in the frames, an electric contact on each frame, an elastic flexible and extensible abutment traversing and arranged below and yieldable to each of the frames and adapted to be engaged by the contact of each frame when the latter descends and itself forming an electric contact, electric-circuit terminals on each frame insulated from each other and adapted to be bridged by a heddle when the latter is allowed by its warp-thread to fall, an electro-magnet, and means to form an electric circuit in which the magnet is arranged including conductor means on each frame connecting one terminal and the corresponding contact on such frame and conductor means connecting the other terminal and the abutment means.
